UNITED STATES PATENT OFFICE

95,795

DESIGN FOR LACE

Harry B. Barnum, Stratford, Conn., assignor to
The American Fabrics Company, Bridgeport, Conn.

Application March 13, 1935, Serial No. 55,858

Term of patent 7 years

To all whom it may concern:

Be it known that I, Harry B. Barnum, a citizen of the United States, residing at No. 166 Warwick Avenue, in the county of Fairfield, town of Stratford, State of Connecticut, have invented a new, original, and ornamental Design for Lace, of which the following is a specification, reference being had to the accompanying drawing, forming part hereof.

The drawing shows a face view of a piece of lace embodying my design.

I claim:

The ornamental design for lace, substantially as shown.

HARRY B. BARNUM.
